CLAIM

The ornamental design for an electronic data storage wristband, as shown and described.

DESCRIPTION

FIG. 1 is a perspective view of a electronic data storage wristband, showing my new design;

FIG. 2 is a front elevational view, thereof, the rear elevational view being a mirror image, thereof;

FIG. 3 is a top plan view, thereof;

FIG. 4 is a bottom plan view, thereof;

FIG. 5 is a side elevational view, thereof, the opposite side elevational view being a mirror image, thereof; and,

FIG. 6 is a view as in FIG. 1, but showing the article in an uncoupled, alternative configuration.
